UNITED STATES PATENT OFFICE.

LLOYD G. WHITE, OF HAVERHILL, MASSACHUSETTS, ASSIGNOR TO UNITED SHOE MACHINERY COMPANY, OF PATERSON, NEW JERSEY, A CORPORATION OF NEW JERSEY.

TACK-PULLING MACHINE.

1,174,214.

Specification of Letters Patent. Patented Mar. 7, 1916.

Application filed May 4, 1912. Serial No. 695,293.

To all whom it may concern:

Be it known that I, LLOYD G. WHITE, a citizen of the United States, residing at Haverhill, in the county of Essex and State 5 of Massachusetts, have invented certain new and useful Improvements in Tack-Pulling Machines; and I do hereby declare the following to be a full, clear, and exact description of the invention, such as will enable others skilled in the art to which it 10 appertains to make and use the same.

The present invention relates to machines for operating upon boots and shoes, and more particularly to machines of this type 15 which are employed for removing the temporary fasteners which are inserted during the manufacture of the shoe.

The object of the present invention is to provide an improved machine of this character which operates efficiently to remove both 20 side and insole tacks.

With this object in view, the various features of the invention consist in certain novel features of construction, combinations and 25 arrangements of parts hereinafter described and claimed, the advantages of which will be obvious to those skilled in the art from the following description.

In the accompanying drawings illustrating 30 the preferred form of the invention; Figure 1 represents an elevation of a machine embodying the several features of the invention in their preferred form; Fig. 2 is a detail showing a front elevation of the 35 tack pulling jaws and a portion of the operating mechanism therefor; Fig. 3 is a detail showing a partial side elevation of the tack pulling jaws and operating mechanism when engaged in removing a side tack from a 40 shoe; and Fig. 4 is a detail illustrating the tack pulling jaws and coöperating foot when engaged in removing an insole tack from a shoe.

The present invention is embodied in a machine consisting essentially of two coöperating 45 tack pulling jaws and suitable actuating mechanism therefor to impart to the jaws tack engaging, tack pulling and tack releasing movements in the sequence named. The tack 50 engaging movement of the jaws comprises a bodily movement of the jaws toward the tack and toward one another in a plane angularly disposed to the direction of the tack pulling movement which takes place in a 55 linear direction to pull the tack substan-

tially in the direction of its length. In the preferred form of the invention, the tack pulling jaws are first caused to descend beneath the head of the tack and are then advanced toward the tack and simultaneously 60 moved toward one another to position them beneath the head of the tack and cause them to grip the tack firmly. It is desirable particularly when removing insole tacks to impart a series of short quick movements to 65 the jaws toward and from the tack to cause them to dig into the sole and engage beneath the head of the tack and to this end a plurality of opening and closing movements are imparted to the jaws when they 70 are positioned upon opposite sides of the tack. As the insole tacks are often embedded deeply in the sole, it is desirable to support them against the thrust of the tack pulling jaws and thus prevent the bending 75 over or breaking off of the tack in the shoe. In the simplest and most efficient form of the invention which has yet been devised, this is accomplished by the provision of a movable foot which engages the head of 80 the tack opposite the tack pulling jaws and maintains the tack in an upright position during its removal from the shoe.

In the machine shown in the drawings, the two tack pulling jaws are indicated at 1 and 85 2 and are supported upon the outer end of a jaw carrying arm 3 pivotally connected to the frame of the machine at 4. The arm 3 is actuated by a cam 6 secured to a cam shaft 8 journaled in the machine frame and continuously rotated by a drive pulley 10. The cam 6 oscillates the arm 3 in a vertical direction about the fulcrum 4 to cause the tack pulling jaws to approach toward and recede from the shoe. The two jaws are pivotally 90 connected by a stud 12 which is secured in a head 13 having trunnions 14 journaled in the bifurcated outer end of the arm 3. With this construction, the jaws are enabled to move toward and from one another and to 100 swing bodily about the axis of the trunnions 14. The tension spring 15 connecting the upper ends of the jaws serves to normally space the lower ends apart until closed by a wedge-shaped cam 17 secured to the outer 105 end of an arm 19 arranged to move downwardly between the upper beveled ends of the jaws. The arm 19 is pivoted to the frame of the machine at 20 and is actuated by a cam 21 secured to the cam shaft 8. Just 110

prior to engaging with the tack, the jaws are rapidly opened and closed to cause them to dig into the sole beneath the head of the tack and to this end the cam 21 is provided with a recess 22 and a cutaway portion 23 in its periphery to cause the jaws to first move toward one another, then separate and finally close and grip the tack while it is being pulled. In order to permit the arm 19 to follow the contour of the cam closely, it is provided with a depending lug 24 which is arranged to enter the recess 22. Both of the arms 3 and 19 are caused to permanently engage with their respective cams, by a tension spring 27 connected at its opposite ends to the arms and tending to draw them together. The lower ends of the jaws are moved substantially parallel to the plane of the sole by an arm 25 having a forked outer end which is pivotally connected to the two jaws by a transverse stud 26. The arm 25 is actuated by an eccentric secured to the shaft 8 and connected to the arm through an eccentric strap formed integral therewith. The shoe is supported in the proper relation to the tack pulling jaws by a downhold 28 rigidly secured to the frame of the machine and engaging with the shoe in close proximity to the tack to be removed. In order to positively open the jaws and release the tack after it has been removed from the shoe, a wedge member 29 is rigidly connected to the downhold 28 and is arranged to engage between the lower ends of the jaws when they have reached the upper limit of movement and are retracted by the arm 25.

When removing insole tacks, it is desirable to provide means for resisting the side thrust upon the tack and prevent an undue bending of the tack when engaged by the pulling jaws. To this end a movable foot 30 is pivotally connected at 31 to a rigid arm 32 and is operatively connected at its upper end to a link 33. The link 33 is actuated by a suitably designed eccentric secured to the shaft 8 and serves to oscillate the foot 30 about its pivotal connection 31 moving the lower end of the foot into engagement with the tack to maintain the tack in an upright position when being pulled.

The operation of the improved machine is as follows:—Assuming that the tack pulling jaws are spaced apart in readiness to descend and engage a tack, the jaw supporting arm 3 is first oscillated about the fulcrum 4 to lower the jaws into a plane located beneath the head of the tack and normal to the shank and which may be conveniently referred to as the plane of the work. The lower tack engaging ends of the jaws are then advanced by the arm 25 and at the same time the jaws are moved toward one another by the entrance of the wedge-shaped member 17 between the upper beveled ends of the jaws. As shown clearly in Fig. 2, the

tack engaging edges of the jaws are oblique to one another and the diagonal movement of the jaws enables them to grasp a tack firmly beneath the head without liability of bending or breaking the tack. In order to further facilitate the engagement of the tacks, especially those which are embedded in the insole, the jaws are first closed by the cam 17 and are then allowed to open prior to the final closing of the jaws to grip and hold the tack during its removal. Thus the jaws are given a plurality of quick movements toward and from one another which facilitates digging into the surface of the sole to get beneath the head of the tack. After the jaws have closed upon the tack, the arm 3 is oscillated to impart a tack pulling movement to the jaws in a substantially linear direction to remove the tack in the direction of its length, as shown clearly in Figs. 3 and 4. During this upward or tack pulling movement of the jaws, the shoe is held stationary by the downhold 28 and when the jaws have completed the removal of the tack from the shoe they are retracted by the arm 25 and at the same time are positively opened by a wedge member 29 which enters between the lower end of the jaws and serves to positively open them if the spring 15 fails to act. After the tack has been released, the jaws again descend and the cycle of operations is repeated.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:—

1. A tack pulling machine having, in combination, a pair of coöperating tack pulling jaws, a downhold for positioning the shoe relative to the jaws, and actuating mechanism for the jaws arranged to impart simultaneously a bodily movement of the jaws toward the tack and toward one another to cause the jaws to engage the tack and a tack pulling movement in a plane inclined to the direction of the tack engaging movement to pull the tack in the direction of its length.

2. A tack pulling machine having, in combination, a pair of coöperating tack pulling jaws, a downhold for positioning the shoe in the proper relation to the jaws, actuating mechanism for the jaws, and means coöperating with the jaws and arranged to move into engagement with and hold the tack against the thrust of the tack pulling jaws during the engagement of the tack by the jaws.

3. A tack pulling machine having, in combination, a pair of coöperating tack pulling

jaws, actuating mechanism for the jaws, a downhold for positioning the shoe in the proper relation to the jaws, and a movable foot arranged to engage and maintain the tack in an upright position while being removed by the tack pulling jaws.

4. A tack pulling machine having, in combination, a jaw supporting arm, a pair of tack pulling jaws pivoted to the outer end 10 of the arm, mechanism for oscillating the arm to raise and lower the jaws, and mechanism for moving the jaws toward and from one another.

5. A tack pulling machine having, in combination, an arm, a pair of tack pulling jaws supported upon the outer end of the arm, mechanism for actuating the arm to raise and lower the jaws, means for moving the jaws toward and from one another, and 20 means for oscillating the two jaws about the arm to advance and retract the lower tack engaging ends of the jaws.

6. A tack pulling machine having, in combination, a pair of tack pulling jaws, a jaw supporting arm, mechanism for actuating the arm, means for advancing and retracting 25

the jaws, and means for positively opening the jaws when they are retracted to cause the tack to be released.

7. A tack pulling machine having, in combination, a pair of coöperating tack pulling jaws, a downhold for positioning the shoe relative to the jaws, and actuating mechanism for imparting a tack engaging movement to the jaws comprising a plurality of 30 movements of the jaws toward and from the tack to enable the jaws to engage beneath the head of the tack.

8. A tack pulling machine having, in combination, a pair of coöperating tack pulling 40 jaws, a downhold for positioning the shoe relative to the jaws, mechanism for advancing the jaws toward the tack, and mechanism for imparting a plurality of opening 45 and closing movements to the jaws when in close proximity to the tack to cause the jaws to engage beneath the head of the tack.
